COIN CONTROLLED FOUNTAIN PEN FILLING DEVICE

Filed Feb. 2, 1927

UNITED STATES PATENT OFFICE

CLIFFORD L. SIRMANS, OF EL PASO, TEXAS

COIN-CONTROLLED FOUNTAIN-PEN-FILLING DEVICE

Application filed February 2, 1927. Serial No. 165,401.

This invention relates to a coin controlled fountain pen filling device, more specifically to a coin controlled mechanism for normally covering the entrance to an ink well, said covering being removable so that the fountain pen may be introduced into the ink well only after a coin of a desired value has been introduced into the machine.

The object of the invention is to produce a simple coin controlled mechanism of the character specified that can be cheaply manufactured and does not readily get out of repair.

A second object of the invention is to produce a device wherein the ink is normally kept from evaporation by keeping tightly enclosed the ink well entrance opening.

Another object of the invention is to produce a device that may be placed on the desk in hotel registration offices without taking up too much room and will present an attractive appearance in connection with the other articles usually kept at such places.

With these and other objects which will appear as the specification proceeds, I will now describe my invention in connection with the appended drawings in which:

Fig. 1 is a top plan view of my device with cut away portions to better illustrate the mechanism below.

Fig. 2 is a sectional view on the line 2—2 of Fig. 1.

Fig. 3 is a view on the line 3—3 of Fig. 1.

Fig. 4 is a section on the line 4—4 of Fig. 1, these views looking in the direction of the arrows.

Fig. 5 is a bottom view of the coin slide; and,

Fig. 6 is a top view of a plate beneath the coin slide, and a coin lever.

The outside casing 1 may be conveniently made in the shape illustrated in Figs. 1 and 2 and may be of either wood or metal attractively finished on the exterior. On one side of the casing may be a door or other removable cover 2 which, when removed, will allow an ink well 3 to be inserted in the casing and securely held therein by means of a guide chute 4 extending from just within the door or cover 2, to and just beyond the

middle point of the casing. This chute or guideway 4 has a slot 5 therein and the ink well 3 is constructed with an outwardly flanged mouth, the flanged portion of which fits in the chute as best shown in Fig. 2 and 55 centers the ink well in the casing 1. However, by opening the door 2 and grasping the ink well it may be removed from the casing for filling purposes and after being filled, the flanges of the mouth of the ink well may 60 be inserted in the chute or guideway and the ink well forced back into the casing with the flange of the neck running in the guideway as best shown in Fig. 4, and the door 2 closed.

I prefer to form a depression 6 in the bottom of the ink well so that when a fountain pen rests in the depression, practically the last of the ink in the ink well can be drawn up into the fountain pen. The ink well 70 bottom, moreover, may be inclined as shown in Fig. 2 to facilitate the ink running into the depression 6.

Across the top of the casing to which the chute or guideway is attached, I provide a strip 7 and between this strip 7 and the top 8 of the casing, I provide a slide 9 having a portion 9' to fit over the mouth of the ink well, there being a hole 8' cut in the top of the casing and a corresponding hole 7' cut 80 in the strip 7, through which a fountain pen may be introduced into the mouth of the ink well when the portion 9' of the slide 9 is pushed to the right as shown in Fig. 2, there being a hole 9'' cut away in the slide portion 9' and when this hole 9'' coincides with the cut away portion 8' in the top of the casing, and the cut away portion 7' in the strip 7 all coincide, the pen may be introduced into the ink well and filled and then removed.

The slide 9 is coin controlled and the coin controlled features comprise a lever 10 pivoted at 11 to the slide 9 and extending to the left as shown in Fig. 1. The lever 10 has cut away portion 10' at its end and in the top 90 of the casing there is a hole 12 just large enough to receive a coin of any desired denomination, preferably a nickel. The end 10' of lever 10, of course, is covered by the top of the casing. The lever 10 has a spring 13 tend-

ing to force it toward the coin inserted in the hole 12 as shown in Fig. 1, sufficiently to come slightly against the periphery of the coin in the hole 12, but remaining covered by the top of the casing. When the coin is inserted in the hole 12 it will rest on an underlying plate 18. The lever 10 rests in a slot (Fig. 1) in the plate 18 and the lever has a lug 24 on its side. F is a supplementary slide movable back and forth over the plate 18. When the slide F is pushed to the right as shown in Figs. 1 and 2, the end 10' of the lever 10 will be pushed aside if a coin has been inserted, by contact of the coin with the lug 24 and the end 10' will be brought into the path of a strip 15 on the slide F. The strip 15 has a notch therein 16 with an inclined side as shown in Figs. 1 and 5 and the inclined side of this notch will be moved in contact with the lever end 10' as the slide continues to move and the inclined side of the slot will slightly move the end 10' away from the coin to loosen the pressure on the coin and further movement of the slide will carry the coin to the right, as shown in Fig. 2, to a hole 18' and allow it to drop into a coin container 20. The supplementary slide F has a handle 21 projecting up through a slot 22 in the top of the casing. This slot allows the handle 21 to be moved to the right as shown in Fig. 1. It will thus be apparent that as the slide F is pushed to the right, it does not at first move the slide 9, but a continuous movement to the right of the supplementary slide F will carry the slide 9 to the right as shown in Fig. 1 until the holes 8' 9" and 7' register, allowing a fountain pen to be introduced into the ink well. After the pen is filled, a spring 27 having a casing 28 to prevent an accumulation of coins from coming in front of a lug to which the spring 27 is connected as shown best in Fig. 3, will draw the supplementary slide F to the left as shown in Fig. 2 and restore the parts to their normal position, the lug 24 on the end of the lever 10 at this time engaging with the right hand wall of the slot 25 as shown in Fig. 1, to move the slide 9 to the left and close the entrance to the ink well.

Extending down from the lever 10 is a projection 28' with a cut away portion 18' to extend around the coin and helps to locate the same over the hole 30 in the top of the coin receptacle 20 into which the coin drops just before the hole 9" registers with the hole 8'.

A door 35 with the usual lock 36 may be provided for convenient removal of the coins in the coin receptacle 20.

To firmly attach the guide chute 4 to the strip 7, I may provide a strip 38 as shown in Fig. 4 extending from the strip 7 downwardly and under the guide chute 4.

Having described my coin controlled foun-

tain pen filling device and the operation thereof, what I claim as new is:

1. A coin controlled fountain pen filling device comprising a casing having a coin slot in its top, a hand-operable slide movable in a plane below and parallel with said top and having a coin receiving opening normally resting below said slot, the casing top having a pen receiving hole therein, a cover slide for the hole, a lever pivoted to the cover slide and operative by a coin inserted in the coin receiving opening with means on the lever and the hand-operable slide for connecting and disconnecting the two slides. 70

2. A coin controlled fountain pen filling mechanism comprising a casing having a coin slot and a pen receiving hole in its top, a hand-operable slide having a coin receiving hole therein beneath said slot, a cover slide beneath said pen receiving hole and means including a lever having a lug thereon operable by a coin inserted in the coin receiving hole for connecting the two slides. 75 80

3. A coin controlled fountain pen filling mechanism comprising a casing having a coin slot and pen receiving hole in its top, a hand-operable slide having a coin receiving hole therein beneath said slot, a cover slide operable in the same horizontal plane as the hand slide and a coin controlled lever pivoted to 90 the cover slide and operable by a coin inserted in the coin receiving hole for connecting the two slides. 95

4. A fountain pen filling device comprising a casing, an ink well in the casing having an opening in its top portion and coin controlled mechanism for opening and closing the well comprising a slide hand operable in one direction, a spring for operating it in the other direction, a second slide movable 100 with the hand operable slide in both directions and in the same horizontal plane and a coin controlled lever between the slides pivoted to one slide and connectable to the other but permitting lost motion between the slides. 105

In testimony whereof I affix my signature.
